US0D1018228S

(12) **United States Design Patent** (10) **Patent No.:** **US D1,018,228 S**
(45) **Date of Patent:** **** Mar. 19, 2024**

(54) **CONNECTOR FOR A POLE SAW**

(71) Applicant: **Ruihong Lin**, Guangdong (CN)

(72) Inventor: **Ruihong Lin**, Guangdong (CN)

(**) Term: **15 Years**

(21) Appl. No.: **29/914,982**

(22) Filed: **Oct. 24, 2023**

(51) **LOC (14) Cl.** **08-03**

(52) **U.S. Cl.**

USPC **D8/9**; D8/97; D8/107

(58) **Field of Classification Search**

(57) **CLAIM**

The ornamental design for a connector for a pole saw, as shown and described.

DESCRIPTION

FIG. 1 is a front elevation view of a connector for a pole saw showing the new design;

FIG. 2 is a back elevation view thereof;

FIG. 3 is a left-side elevation view thereof;

FIG. 4 is a right-side elevation view thereof;

FIG. 5 is a top plan view thereof;

FIG. 6 is a bottom plan view thereof;

FIG. 7 is a perspective view thereof; and,

FIG. 8 is another perspective view thereof.

The broken lines showing of the pole illustrates the environment of the claimed design and forms no part thereof. The remaining broken lines in the drawings illustrate portions of the connector for a pole saw and form no part of the claimed design.

1 Claim, 8 Drawing Sheets
